UNITED STATES PATENT OFFICE.

AXEL H. STAF, OF PROVIDENCE, RHODE ISLAND, ASSIGNOR TO THE ALVIN CORPORATION, OF NEW YORK, N. Y.

DESIGN FOR A SPOON OR SIMILAR ARTICLE.

Application filed October 13, 1928. Serial No. 28,478. Term of patent 14 years.

To all whom it may concern:

Be it known that I, AXEL H. STAF, a citizen of the United States, residing at Providence, in the county of Providence and State of Rhode Island, have invented a new, original, and ornamental Design for a Spoon or Similar Article, of which the following is a specification, reference being had to the accompanying drawings, forming part thereof.

Figure 1 is an obverse view of a spoon or similar article, showing my new design.

Figure 2 is a fragmentary showing of the reverse of Fig. 1, and

Figure 3 is an enlarged section of the same on line 3—3 of Figure 1.

I claim:

The ornamental design for a spoon, or similar article, as shown.

In testimony whereof I have signed my name to this specification.

AXEL H. STAF.
